(57) **CLAIM**

The ornamental design for an electronic wrist band, as shown and described.

DESCRIPTION

FIG. 1 is a perspective view of an electronic wrist band showing our new design in a first configuration;

FIG. 2 is a top view of the electronic wrist band of FIG. 1; FIG. 3 is a bottom view of the electronic wrist band of FIG. 1;

FIG. 4 is an end view of the electronic wrist band of FIG. 1; FIG. 5 is an opposite end view of the electronic wrist band of FIG. 1;

FIG. 6 is a side view of the electronic wrist band of FIG. 1; FIG. 7 is a perspective view of an electronic wrist band showing our new design in a second configuration; FIG. 8 is a top view of the electronic wrist band of FIG. 7; FIG. 9 is a bottom view of the electronic wrist band of FIG. 7;

FIG. 10 is an end view of the electronic wrist band of FIG. 7;

FIG. 11 is an opposite end view of the electronic wrist band of FIG. 7; and,

FIG. 12 is a side view of the electronic wrist band of FIG. 7.

The broken lines in FIGS. 1, 2, 4, 7, 8, and 10 show portions of the electronic wrist band that form no part of the claimed design.
